US00D571816S

(12) **United States Design Patent**
Corcoran et al.

(10) **Patent No.:** US D571,816 S
(45) **Date of Patent:** ** Jun. 24, 2008

(54) **COMPUTER MOUSE TOPCASE**

(75) Inventors: **Fergal Corcoran**, Co. Cork (IE);
Norman Stevenson, Wexford County
(IE); **Niall White**, Tipperary (IE); **Peter
Sheehan**, New Castle County Wicklow
(IE); **Michelle Fishberg**, East Palo Alto,
CA (US); **Ken Delaney**, England (GB);
Erik Charlton, Atherton, CA (US);
Kevin Forde, Cork (IE)

(73) Assignee: **Logitech Europe S.A. (CH)**

(**) Term: **14 Years**

(21) Appl. No.: **29/261,820**

(22) Filed: **Jun. 19, 2006**

(51) **LOC (8) Cl. 14-02**

(52) **U.S. Cl. D14/454; D14/409**

(57) **CLAIM**

The ornamental design for computer mouse topcase, as shown and described.

DESCRIPTION

FIG. 1 is a perspective view of a computer mouse topcase showing our new design;

FIG. 2 is a top plan view thereof;

FIG. 3 is a right elevational view thereof;

FIG. 4 is a left elevational view thereof;

FIG. 5 is a front elevational view thereof;

FIG. 6 is a rear elevational view thereof; and,

FIG. 7 is a bottom plan view thereof.

The broken line showing of a mouse is included for the purpose of illustrating environment and forms no part of the claimed design.
